UNITED STATES PATENT OFFICE.

CHARLES B. KELLOGG, OF CHICAGO, ILLINOIS.

DISPLAY CARD.

Application filed June 22, 1922. Serial No. 570,208.

To all whom it may concern:

Be it known that I, CHARLES B. KELLOGG, a citizen of the United States, residing at Chicago, in the county of Cook and State of Illinois, have invented certain new and useful Improvements in Display Cards, of which the following is a specification, reference being had to the accompanying drawings, and to the reference characters marked thereon, which form a part of this specification.

This invention relates to display cards or easels, designed for use for advertising purposes, and more particularly to that type of display card which may be cut out of a single piece of cardboard or other suitable material, and which when folded and assembled as designed, will stand in a vertical position without the aid of separate brace pieces or the like.

The device is particularly designed for the display and advertisement of articles of food, and to that end one of the objects of the invention is to produce a display card which will simulate a table, with two or more persons in juxtaposition thereto, upon which table articles of food may be physically placed.

The invention consists in the novel device herein illustrated, described and more particularly pointed out in the appended claims.

In the drawings:

Fig. 1 is a perspective view of a device embodying one form of my invention, fully assembled and standing in an upright position.

Fig. 2 is a plan view of the blank, laid flat, from which the card shown in perspective in Fig. 1 is formed.

Fig. 3 is a similar view of a modified form.

In the drawings (referring particularly to Fig. 2) A represents a sheet, preferably of cardboard, having a straight margin *a* constituting the base of the device when assembled. A table top *B* and front support *C* therefor are formed by cutting along the lines *c*, *c*, *c'*, *c'*, scoring along the lines *c²*, *c²*, and cutting along the lines *c³*, *c³*, *c⁴*, *c⁴*, continuing into the lines *b*, *b*, of the table top *B*. The support *C* will maintain a vertical position and by means of scoring along the line *b'* the table top *B* is made to assume a horizontal position.

Joined to the table support *C* and adapted

to be bent back at right angles thereto, by means of the scored lines *c²*, *c²*, are two side pieces *D*, *D*, the top margins *d*, *d*, of which are formed by horizontal cutting, and are adapted to cooperate with the front support *C* in supporting the table top *B*.

Attached to the side portions *D*, *D*, and separated therefrom by the scored lines *d'*, *d'*, are members *E*, *E*, which are to be given such shape and decoration as the particular use of the device as a whole may require; for example, to simulate a pair of chairs with a person seated upon each. These members *E*, *E*, are formed by cutting elongated slots, *e*, *e*, the lower margins thereof being a continuation of the top margins *d*, *d*, of the side portions *D*, *D*. The outlines of the figures *e'* and of the chairs *e²* of the members *E*, *E*, are then cut in any design or contour desired. It will be understood that by bending the device along the lines *d'*, *d'*, the sections *E*, *E*, will rest upon the base *a* at right angles to the sections *D*, *D*, and parallel to the front support *C*. It will also be noted that by cutting the slots *e*, *e*, as described, lugs *e³*, *e³*, are formed on that part of the sections *E* constituting the figures, which lugs are adapted to cooperate with slots *b²*, *b²*, cut in the table top *B*. The insertion of the lugs *e³* in the slots *b²* serves to hold the side members *D* in proper position at right angles to the front support *C*.

The extreme outer sections *F*, *F*, are adapted to be bent backwardly by bending along the scored lines *e⁴*, so as to stand at substantially right angles to the members *E* when the device is assembled; and thus the sections *F*, *F*, act as braces for the side members *E*, *E*.

G represents a back member having a lower margin *g*, side margins *g'*, *g'*, and a top margin *g²*. The side margins have lugs *g³*, which are designed to enter slots *f*, *f*, in the brace sections *F*, *F*, to lock these members together. This member *G* is designed to be bent upwardly, along the scored line *g*, into a vertical position, at right angles to the table top *B*, and it may be decorated in any suitable manner, as for example, a third person seated at the table *B* or a servant presenting a dish or article of food.

Referring now to Fig. 3, it will be seen that the various sections are identical with

those shown and described with reference to Fig. 2, excepting that the rear section G has been left out, and in place thereof is shown a member H, which is bent down-
wardly along the scored line h. The lugs h', h', on the side margins of this member H are adapted to be inserted in the slots f, f, of the members F, F.

In this modified form, it will be understood, only two persons will be represented as sitting at table, and the member H is merely designed to assist in holding the parts in assembled relation.

It will be understood that, as shown in Fig. 2, and in the perspective view, Fig. 1, the servant may be shown as placing upon the table the article it is desired to advertise, by merely painting, printing or otherwise upon the display card, but manifestly actual exhibits may be placed upon the table top B for display purposes.

The device is attractive, and as heretofore stated is so arranged that it may be cut from a single piece of heavy paper or card-board, which permits it to be laid flat in shipping. Another advantage is the elimination of separate parts, flaps or braces which are usually required to be glued to the device, and which not only become separated therefrom in use, but do not constitute the firm, unitary structure produced by means of my invention.

It is especially to be noted that the table top B is firmly and securely locked in position and supported, and moreover is of such size as to receive and support physically a specimen of the article which the display card is being used to advertise.

It will be obvious, referring to that form shown in Fig. 3, that the members F, F, and the rear section H may be dispensed with, and a brace member such as indicated in dotted lines, may be used to assist in supporting the table top B.

45 I claim as my invention:

1. A display card made from a single blank, comprising a table top having front and side supports, and side members shaped to a predetermined design attached to the side supports, said side members being interlocked with the table top intermediate the rear and front edges thereof.

50 2. A display card made from a single blank, comprising a table top having front and side supports, side members attached to said side supports, and shaped to a predetermined design, brace members attached to the side members, a rear section attached to the rear margin of the table top and means for locking the latter to the brace members.

55 3. A display card made from a single blank, comprising a table top having front and side supports, side members attached to said side supports, and shaped to a predetermined design, brace members attached

to the side members, a rear section attached to the rear of the table top, and means for locking the latter to the brace members.

4. A display card made from a single blank, comprising a table top having front and side supports, side members attached to said side supports, and shaped to a predetermined design, brace members attached to the side members, a rear section, means for locking the latter to the brace members, 70 and interlocking means between the side members and the table top.

5. A display card made from a single blank, comprising a table top having front and side supports, side members attached to said side supports, and shaped to a predetermined design, brace members attached to the side members, a rear section, means for locking the latter to the brace members, and interlocking means between the side members and the table top, 75 said means comprising a lug on the side member and a slot in the table top.

6. A display card made from a single blank, comprising a table top having front and side supports, the side supports being of a width less than the width of the table top, side members attached to said side supports, and shaped to a predetermined design, 90 said side member being interlocked with the table top intermediate the rear and front edges of the table top, brace members attached to the side members, a rear section and means for locking the latter to the brace members.

7. A display card made from a single blank, comprising a table top having front and side supports, the side supports being of a width less than the width of the table top, side members attached to said side supports, and shaped to a predetermined design, 95 said side member being interlocked with the table top intermediate the rear and front edges of the table top, brace members attached to the side members, a rear section attached to the rear of the table top, and means for locking the latter to the brace members.

8. A display card made from a single blank, comprising a table top having front and side supports, the side supports being of a width less than the width of the table top, side members attached to said side supports and shaped to a predetermined design, 115 said side member being interlocked with the table to intermediate the rear and front edges of the table top, brace members attached to the side members, a rear section and means for locking the latter to the brace members, and interlocking means between the side members and the table top.

9. A display card made from a single blank, comprising a table top having front and side supports, side members attached to said side supports and shaped to repre- 120 125 130

- sent the outline of a person seated upon a chair, brace members attached to the side members, a rear section attached to the rear margin of the table top and means for locking the latter to the brace members.
10. A display card made from a single blank, comprising a table top having front and side supports, side members attached to said side supports and shaped to represent the outline of a person seated upon a chair, brace members attached to the side members, a rear section attached to the rear of the table top, and means for locking the latter to the brace members.
15. 11. A display card made from a single blank, comprising a table top having front and side supports, side members attached to said side supports and shaped to represent the outline of a person seated upon a chair, brace members attached to the side members, a rear section, means for locking the latter to the brace members, and inter-
- locking means between the side members and the table top.
12. A display card made from a single blank, comprising a table top having front and side supports, side members attached to said side supports and shaped to represent the outline of a person seated upon a chair, brace members attached to the side members, a rear section, means for locking the latter to the brace members, and interlocking means between the side members and the table top, said means comprising a lug on the side member and a slot in the table top.

In testimony that I claim the foregoing as my invention I affix my signature, in the presence of two witnesses, this 20th day of June, 1922.

CHARLES B. KELLOGG.
